A. B. SPACH

STETHOSCOPE

Filed June 27, 1921

Inventor:
Aurel B. Spach
H. J. D. *Spach*
Attorneys

UNITED STATES PATENT OFFICE.

SAMUEL B. SPACH, OF CHICAGO, ILLINOIS.

STETHOSCOPE.

Application filed June 27, 1921. Serial No. 480,571.

To all whom it may concern:

Be it known that I, SAMUEL B. SPACH, a citizen of the United States, and a resident of Chicago, in the county of Cook and State of Illinois, have invented certain new and useful Improvements in Stethoscopes, of which the following is a description, reference being had to the accompanying drawing, which forms a part of my specification.

10 My invention relates to a stethoscope, with a portion of the invention pertaining more particularly to the binaural type of stethoscope and having for its object the provision of means whereby the binaurals 15 may be readily adjusted to the varying shapes of the external auditory meatus or opening of the external ears, thereby not only providing a more comfortable stethoscope of the type mentioned, but also thereby providing an instrument adapted to fit more closely to the ear-openings so as to transmit the sound waves without loss as, however, has been the case with stethoscopes heretofore employed wherein an improper 20 fitting of the ear-piece resulted because of the non-adjustability of the binaurals of the stethoscope.

Another portion of the invention relates to the stethoscope proper and has for its 30 object the provision of a stethoscope whereby all sound waves entering the bell of the instrument will be brought to a focus and completely transmitted through the aural pieces of the stethoscope; the stethoscope proper being so constructed that an augmenter or resonator is provided adjacent to the bell portion of the instrument so that the vibrations or resultant sound waves will be 35 conveyed in accentuated condition and under 40 more or less control of the diagnostician, while the over tones may be substantially eliminated or entirely suppressed.

A further object of my invention is to provide a stethoscope wherein the augmenter 45 or resonator is so formed and constructed that it may be adjustable as to dimensions and its capacity thereby increased or diminished at the will of the operator; with said resonator, however, so formed, whether in 50 extended or contracted condition, that the principal tones will be conveyed by the sound waves to the ear in accentuated condition, while at the same time the contact

sounds will be reduced to a minimum and any over tones more or less suppressed.

The objects and advantages of my invention will be more readily comprehended from the detailed description of the accompanying drawing, wherein:

Figure 1 illustrates my improved stethoscope in elevation.

Figure 2 is a detail sectional view of one of the aural members of the stethoscope and its holding member.

Figure 3 is a longitudinal sectional view, 65 of the main or body portion of my improved stethoscope with its aural piece or tube receiving portion.

Figure 4 is a longitudinal sectional view 70 of the main or bell portion of my improved stethoscope shown in distended condition.

Figure 5 is a detail view of a portion of the adjustable bracket or holding member 75 for the aural members of the stethoscope.

Figure 6 is an enlarged detail sectional view, taken on the line 6—6 of Figure 1, looking in the direction of the arrows, with portions broken away.

In the exemplification of the invention, as illustrated in the drawing, it comprises the body or bell portion 10 which is internally formed with a parabolic curved surface so that all sounds encountered by any part of the bell interior will be brought to a focus and be conveyed through a suitable channel 80 or passage 11, at the vertex of the bell, into an augmenter or resonator 12, consisting of preferably two tubular members 13 and 14 arranged in telescopic relation with each other. The tubular member 13 is preferably 85 formed integral with or immovably secured to the apex of the bell portion of the stethoscope. In the particular exemplification, the bell portion 10, at its apex or outlet end, is shown provided with an elongated stem portion 15, shown of more or less thickness, through which the passage 11 is disposed and the end of the stem 15 within the shell 13 is provided with an arcuate or substantially semi-spherical surface 16; while the 90 opposite or outer end of the cylindrical shell or tube 14 is also provided with an end wall or disc 17 of any proper thickness, with the inner surface of the wall concaved or substantially semi-spherical at 18 in order 95 that the opposite surfaces of the stem or

disc-portion 15 and disc portion 17, in conjunction with the tubular members 13 and 14, will provide a somewhat spherical chamber, at least a chamber somewhat in the nature of an oblate spheroid.

The tubes 13 and 14 are arranged in telescopic relation so as to enable the two arcuate or semi-spherical surfaces 16 and 18 of end walls 15 and 17, respectively, to be brought into such close relation with each other when the tubes are in their maximum contracted relation, that a substantially spherical chamber is provided with the augmenter or resonator portion of the instrument, as more clearly shown in Figure 3; the telescopic relation between tubes 13 and 14 being such as to permit the resonator to be extended into the condition shown in Figure 4, with its semi-spherical or concaved end walls spaced farther apart and thereby producing the oblong or elongated chamber of increased capacity.

The end wall or disc member 17 is shown preferably terminating in a thimble portion 25 which is adapted to receive the end of the sound-conveying tubular member 19, whose outer end is bifurcated to provide the spreading outlets 20, 20 which are each adapted to receive a flexible or rubber tube 21, 21, the ends whereof are attached to or slipped over the metallic or rigid tubes 22, 22 which terminate in suitable apertured ear pieces 23.

The aural portions 22 are adjustably secured together by means of clip members 24, 24 preferably composed of thin sheet metal which is more or less flexible. Each clip member 24 has one end provided with the angular or channel formation as shown at 25; the parallel sides whereof are apertured for the passage of the tubular member 22 and at the same time providing gripping relation with the member 22. The formation of the attaching ends of the clip or holding member as thus far described has been previously employed, but such members were not constructed to permit adjustment of the binaurals in directions lengthwise or transversely of the members as is the case with my improved clip or holding element, wherein each clip or holding member 24 at the inner or overlapping end thereof is provided with an elongated slot 26 adapted for the passage of a suitable thumb or set-screw 27, which, as shown in the drawing, may be provided with a thumb-nut as at 28 to permit easy manipulation of the clamping means which is adapted to hold the clip members 24 in their expanded or contracted relation. The binaurals of stethoscopes as heretofore provided have usually been joined by means of a single spring clip which could only be slightly adjusted to the extent of the flexibility of the metal, which, of course, was in one direction only, but such

bowing or flexing of the metal clip causes an improper disposition or presentation of the ear pieces 23. With my improved construction it is apparent that adjustment may be made in a direction lengthwise of the clip members, as well as in a direction transversely thereof, thereby permitting a separation of the binaurals laterally, or a closer bringing together of the same, which enables them to be adjusted to properly fit the varying shapes of the external auditory meatus or openings of the external ears and without undue pressure.

The perimeter of the bell 10 is preferably provided with a band or ring of rubber, or other non-metallic, non-sound-conveying medium, as at 29, see Figures 3 and 4; the rubber covering for the perimeter of the bell tending to reduce contact sounds and interference sounds to a minimum, so that merely the desired sounds will be conveyed through the instrument and a more precise diagnosis thus permitted.

Constructing the bell with an inner parabolic curved surface, causes all sound waves contacting with the inner surface of the bell to be brought to a common center or focus which results in all of the sound waves being conveyed through the passage 11 disposed at the vertex of the bell; the sound waves in turn being conveyed into the augmenter or resonator before they are transmitted through the aural pieces of the instrument; and the density of these sound waves may be affected or attenuated by enlarging or distending the chamber of the resonator or augmenter to suit the desires or needs of the operator and the conditions under which the diagnosis is being made; while other conditions may necessitate operating with the resonator in normal or contracted condition shown in Figure 3, whereby the density of the sound waves may be increased and complete transmission thereof, through the ear or aural pieces to the ear of the diagnostician thereby enabled. With my improved construction contact sounds are not only reduced to a minimum, but over-tones may be suppressed and principal tones accentuated, through proper manipulation of the telescopic cylinder (whose opposite ends present arcuate or curved surfaces substantially semi-spherical as previously described) whereby the capacity of the chamber or resonator may be increased or diminished at the will of the operator. At the same time my improved stethoscope is so constructed that it may be immediately adjusted to fit the particular shape or formation of the external auditory opening of the ear of the user and the ear pieces made to properly fit into the external ear so that merely the sounds passing through the stethoscope will be conveyed or transmitted into the ear.

In order that the relation between the tubes 13 and 14 of the augmenter or resonator 12 may be readily controlled, namely to enable the easy distention or telescoping 5 of said tubular members, I have shown the outer tube or member 14 provided with a pair of spaced lugs 30 disposed on opposite sides of a slot or opening in said member 14. The lugs 30 provide bearing for the 10 spindle or stem 31 of a thumb-wheel 32 to permit rotation thereof; and the spindle 31, at a point intermediate of the lugs 30 is provided with a small pinion or star wheel 33 which extends through the opening or slot in the member 14 and engages 15 with the rack or toothed surface 34 formed lengthwise of the inner member 13, see Figures 3, 4 and 6. With this construction, it is apparent that rotation of thumb-wheel 20 32 and therefore of star wheel 33, will cause the inner member 13 to be moved outwardly or inwardly depending upon the direction of rotation of the wheel 33. With the 25 pinion meshing with the rack or toothed surface not only permits adjustment of the inner member of the augmenter or resonator, but at the same time will hold the same in its adjusted position against collapsing, and also prevent the inner member 30 with the bell 10 from slipping out of the outer member 14.

The construction shown and described I believe to be the simplest embodiment of my invention and the terms and expressions employed are merely used as terms of description and not of limitation, as there is no intention in the use of such terms and expressions of excluding any mechanical equivalents for the respective features 40 shown and described, as certain structural modifications are possible and may be made without, however, departing from the spirit of my invention.

What I claim is:—

45 1. A stethoscope, comprising a bell portion having an inner parabolic curved surface with an elongated restricted outlet opening at the vertex thereof terminating in a concaved orifice, and a resonator secured to said outlet, provided with a concaved inner end wall, said resonator being composed of a pair of telescopically arranged cylindrical tubes of larger internal diameter than said outlet opening, the outer tubing being provided with a restricted tubular outlet.

50 2. In a stethoscope, an adjustable binaural clip, comprising a pair of correlated curved members, the outer ends whereof are bent to form holding relation with the aural tubes of the stethoscope, while the adjacent ends thereof are adapted to overlap each other with the overlapping end of each member provided with an elongated slot,

and clamping means disposed through the 65 slots of both members whereby longitudinal and lateral adjustment of the members may be had and maintained.

3. In a binaural stethoscope, a pair of clip members, the outer ends whereof are 70 bent to provide a pair of substantial parallel portions disposed perpendicular to the main portions of the members, the substantially parallel portions being apertured to permit the aural elements to slide there- 75 through and be maintained in associated relation, the adjacent ends of the clip members being arranged in lapping relation with each other and longitudinally slot- 80 ted, and means disposed through the slot- 85 ends of the members for adjustably securing the same together and permitting movement in a lengthwise direction or in a direction transversely of the length of said members.

4. A stethoscope, comprising a bell portion having an inner parabolic curved surface, an outlet opening at the vertex of said bell portion, a pair of tubular members arranged in telescopic relation, the inner diameters of the tubular members being larger than said outlet opening, one of said tubular members being secured to the outlet opening of the bell portion while the other tubular member is provided with a restricted outlet, the inner end of the tubular member about the outlet opening of the bell and the inner end wall of the tubular member about its outlet opening being both concaved to provide an oblate spheroidal chamber, and means whereby the telescopic relation of the tubular members may be controlled. 95

5. A stethoscope, comprising a bell portion, a resonator secured to said bell portion and composed of cylindrical members arranged in telescopic relation, and means whereby the telescopic relation of the cylindrical members may be controlled and the internal dimensions of the resonator 100 determined. 105

6. A stethoscope, comprising a bell portion, the inner surface whereof describes a parabolic curve, a resonator composed of a pair of tubular members arranged in telescopic relation with each other, one of said members being secured to the bell portion, while the other is secured to the aural elements of the stethoscope, the connected ends of each member being dished or concaved, 110 and regulable means whereby the telescopic relation between the tubular members may be controlled and the latter held in their adjusted positions. 115
